UNITED STATES PATENT OFFICE

2,508,356

MOTOR

John R. Allsup, Sr., Port Orchard, Wash.

Application March 6, 1947, Serial No. 732,888

1 Claim. (Cl. 103—143)

1

This invention relates to hydraulic motors and pumps and more particularly to the construction of the stationary housing and rotary parts.

It is an object of the present invention to provide a rugged fluid motor or pump which can be used to hydraulically propel automotive vehicles, ships or locomotives and to eliminate the use of mechanical transmission from such conveyances.

It is another object of the present invention to provide a hydraulic motor or pump with a simple timing arrangement for setting the rotary piston elements for use as impellers in the path of the liquid and wherein the entering and leaving passages of the liquid are separated from one another by a simple partition or structure which is a separate part of the main housing and can be removed for replacement after it has been worn and wherein this partition or block is avoided by the rotary piston elements by the timing mechanism.

Other objects of the present invention are to provide a hydraulic motor or pump which is of simple construction, easy to assemble, made of minimum parts and efficient in operation.

For other objects and for a better understanding of the invention reference may be had to the following detailed description taken in connection with the accompanying drawing, in which

Fig. 1 is a longitudinal cross-sectional view of a hydraulic motor or pump embodying the features of the present invention.

Fig. 2 is a cross-sectional view taken on line 2—2 of Fig. 1 and looking in the direction of the arrows thereof and looking upon the timing mechanism connected with the several rotary impellers.

Fig. 3 is a transverse cross-sectional view taken on line 3—3 of Fig. 1 and looking in the direction of the arrows thereof and through the rotary impellers.

Fig. 4 is a side elevational view of the two part rotor containing the rotary valves or impellers.

Fig. 5 is an end elevational view of one of the rotor parts looking at the outer end of the same.

Fig. 6 is an end elevational view of the rotor part which contains the collars of the impellers.

Fig. 7 is an exploded and perspective view of one of the impellers or rotating pistons and of the crank which drives the same.

Fig. 8 is a top plan view of a central ring member in which the collars or enlargement portions of the impellers are guided and worked.

Fig. 9 is a perspective view of the separating partition or block which is secured to the central ring.

Referring now particularly to Figures 1 to 9,

2

there is shown one form of the invention wherein 21 represents one of the casing parts, 22 another of the casing parts and 23 a third one of the casing parts which connects the parts 21 and 22 together while retaining a central ring 24 therebetween. The casing part 21 is threaded as indicated at 25 and also has a radially extending flange 26 at the opposite end. The casing part 22 has a threaded portion 27 of larger diameter than the threaded portion 25 of the casing part 21 and an enlargement providing an eccentric chamber 28 at the opposite end for containing a timing mechanism or disc 29. The casing part 23 is threaded to receive the threaded portions 25 and 27 of the casing parts 21 and 22 and is recessed to receive the ring 24 which has an inner annular channel 31 therein which extends throughout the major part of its inner periphery and which has at its top a radially inwardly extending block 32 providing a partition which closes the channel 31 to separate inlet and outlet passages 33 and 34 extending radially through the casing part 23 and the central ring member 24 at opposite sides of the block 32.

25 Adapted to rotate within the casing parts and the ring 24 is a rotor structure which includes a driving section 35 and a driven section 36 each of which is provided with three longitudinally extending openings 37 for receiving shafts of the rotary impellers 38. Each of the rotor parts have holes 39 for receiving tie-bolts 41 which hold the rotor assembly together. On each of the rotary impellers 38 is an enlargement or collar 42 which is retained in a counter-bore 43 of the openings 37 and the collar is adapted to extend into the channel 31 of the central ring member 24. The parts 35 and 36 are retained against rotational displacement by key 44 adapted to fit recesses 45 on the engaging faces of the parts 35 and 36. 30 The ring 24 is retained against rotational displacement within the casing part 23 by a key 46. The rotor structure also includes an output shaft 47 if the device is used as a motor, which has a flange 48 by which the shaft 47 is connected to the rotor parts 35 and 36 by the tie-bolts 41. 35 Within the casing part 21 are thrust washers 51 and 52 adapted to engage with the flange portion 48 of the shaft 47 and be retained thereagainst to take up the thrust by a casing cover 53 secured to flange 26 of casing part 21 by machine screws 54. This cover is internally threaded as indicated at 55 to retain a packing nut 56 serving to secure a packing 57 about the shaft 47 and within an internally threaded recess 58 in a sleeve portion 59 of the casing cover part 53.

Each of the rotary impellers 38 have an eccentrically positioned pin providing a crank element 61 secured to one end of the same and within the eccentric chamber 28 of the casing part 22. This crank element is secured against rotational displacement on the rotary impeller by pins 62 and is arranged so that the crank extension is in line with a milled off face or gap 63 of a collar 42 of the rotary impeller 38. These cranks 61 are journalled in bearing sleeves 64 lying within circumferentially spaced openings 65 of disc 66 which is rotatably mounted on a projection 67 of a cover plate 68 for the chamber 28. The projection 67 is offset from the center of the rotor the same distance that the crank is offset from the rotary impeller axis. The plate 66 is connected to the projection 67 through a ball bearing unit 69.

In operation when liquid is passed through inlet passage 33 under pressure and into the channel 31, the rotor will be rotated as the impellers 38 approach the separating block 32 they will be turned so that their flattened surface 63 will ride under the block 32 of the ring 24 and free of it. Thereafter the collar is turned so that it will lie in the channel in order to be engaged by the motivating liquid. This timing of the positioning of the rotary impeller is effected by the timing device 29 and after the several rotary impellers 38 arrive at the block 32 they will automatically turn so that their collars 42 can pass beneath it. It should now be apparent that a very durable construction and arrangement is had.

While various changes may be made in the detail construction it shall be understood that such changes shall be within the spirit and scope of the present invention as defined by the appended claim.

I claim:

In a rotary pump, the combination which comprises a rotor including a cylindrical driving section with a plurality of spaced axially disposed cylindrical openings therein spaced from the periphery thereof, said openings having counter-bores positioned at the inner end of the section, and a complementary driven section having cylindrical openings therein positioned in alignment with the said cylindrical openings of the driving section, shafts providing impellers journalled in the said cylindrical openings of the sections of the rotor, said shafts having collars thereon and positioned with the collars in the counter-bores of the openings of the driving section, said collars having flattened surfaces thereon, a housing hav-

ing inlet and outlet connections and having an eccentric chamber in one end, said rotor being rotatably mounted in said housing, an annular ring member in the housing and positioned around said rotor, said ring member having an annular channel in the inner surface thereof and positioned to register with the counter-bores of the said cylindrical openings of the driving section of the rotor whereby the collars of the shafts are received in said inner annular channel, said inner annular channel positioned to communicate with the said inlet and outlet connections of the housing, a block forming a partition mounted in the ring member, extended into said inner annular channel thereof and positioned between the said inlet and outlet connections, pins mounted on the ends of the shafts and eccentrically positioned so as to form cranks, a cover plate providing a closure for the said eccentric chamber of the housing and having a stud extended inwardly therefrom, the axis of said stud positioned in a plane extended midway between the said inlet and outlet connections of the housing and the center of the stud being off-set from the axis of the rotor, a disc journalled on said stud and having equally spaced openings therein in which the said pins of the cranks are journalled whereby upon rotation of the rotor the disc and cranks turn the said shafts so that the flattened surfaces of the collars are within the periphery of the rotor as the collars pass the block forming the partition extended into the said inner annular channel, means connecting the driven section of the rotor to the driving section, and a drive shaft extended from the driving section of the rotor through the end of the housing opposite to that in which the eccentric chamber is positioned.

JOHN R. ALLSUP, Sr.
